to National Malleable and Steel Castings Com-
pany, Cleveland, Ohio, a corporation of Ohio

Application December 17, 1931, Serial No. 581,550

16 Claims. (Cl. 105—197)

My invention relates to trucks for railway cars, and more particularly to the type of truck described in my application filed June 6, 1930, Serial No. 459,480, issued September 11, 1934 as Patent No. 1,973,664. This type of truck employs a plurality of sets of coil springs for the purpose of supporting the bolster, which in turn supports the car. These springs, after a certain amount of use, are apt to acquire a permanent "set", or in other words, the expansive power of such springs weakens somewhat, and the bolster is thereby allowed to ride lower in the truck. This, of course, lowers the entire car frame and coupling mechanism, which latter is thereby at times rendered difficult of manipulation. Under such circumstances it is desirable to "shim" the springs in order to overcome the effect described. The customary periodic turning down of the truck wheels to restore wheel contours also has the effect of lowering the coupler height, with the result that shimming of the truck springs is advisable.

It is the object of the present invention to provide improved means, both simple and efficient, for shimming the springs of trucks of the type disclosed in my earlier application referred to above, and trucks similar thereto. Another object of my invention is to provide means whereby the materials for this operation may be carried on each truck and thereby rendered available at all times. A further object of my invention is to provide means whereby a person engaged in performing the shimming operation may be informed, when such is the case, that the truck has been shimmed as far as is practicable, and that further shims may not be inserted. Another object of my invention is to provide means for compensating for the wear which occurs between the bolster and the walls of the bolster opening in the side frame during service. Other objects and advantages of my invention will appear from the description which follows.

Referring to the drawings, Fig. 1 is a vertical longitudinal section through the central portion of a side frame of the type disclosed in my earlier application described above; Fig. 2 is a horizontal section of a like portion of the side frame, on the line 2—2 of Fig. 1; Fig. 3 is a vertical section similar to Fig. 1, but illustrating another feature of my invention; Fig. 4 is a horizontal section along line 4—4 of Fig. 3, with the bolster in plan; Fig. 5 is a transverse vertical section through one end of the bolster, spring caps, and associated parts, illustrating a modification of my invention; Fig. 6 is a plan view of the parts illustrated

in Fig. 5; Fig. 7 is a fragmentary horizontal section through a side frame and the dowels 4a of a bolster, illustrating a modified form of my invention; Fig. 8 is a fragmentary vertical section on line 8—8 of Fig. 7.

Referring to Fig. 1, the numeral 1 designates the central portion of a side frame, provided with the usual opening 1a to admit the end of the bolster 2. It will of course be understood that the opposite end of the bolster extends into a similar side frame, but for the purposes of the present invention it suffices to consider but one side frame of the car truck and the associated end portion of the bolster. A spring seat 3 forms the bottom of the bolster opening, and is provided with openings 4 through which the cylindrical lugs or dowels 4a of the bolster project into the interior of the tension portion 5 of the side frame, which is of box-section and merges with the side frame tension members 5a. Coil springs 6 are supported upon the discs 6a which are positioned in the seats 6b formed in the lower web or shelf 7 of the tension member 5. Spring caps 8 are seated upon the upper ends of springs 6, and are provided with circular openings 9 centrally located, through which the plugs 9a project downwardly into the interior of the coil springs 6. Bosses 10 project upwardly from the plugs 9a into the interior of the lugs 4a.

A set of two coil springs 11 is arranged in tandem fashion within the bolster 2, along the longitudinal axis of the latter, or in other words transversely of the side frame. Said springs 11 rest upon discs 11a, which, in turn, ordinarily rest upon the spring seat 3. The bolster is carried by springs 11 and springs 6, the lugs 4a ordinarily resting upon spring caps 8. The side frame and bolster construction so far described is shown in my application above referred to. In carrying out the present invention, shims 12 are interposed between the spring caps 8 and the dowels 4a, while shims 13 are shown between the spring seat 3 and the discs 11a. Shims 12 are formed of metal discs of suitable thickness, provided with central openings through which the bosses 10 of the plugs 9a project. The shims 13 are shown of the same thickness as shims 12, but are of a shape best illustrated in Figs. 2 and 4. This shape is necessitated by presence of the dowels 4a, the shims 13 being recessed, as at 14, to accommodate the dowels, and being made sufficiently narrow to be admissible in the space between the dowels. The number and thickness of the shims 12, 13 may of course be varied, the number and thicknesses shown being merely illustrative.

- If desired, a bolt 17 may be inserted in a suitable opening in the wall 18 of column 19, for the purpose of providing an indication of the limit to which the shimming operation may be carried.
- 5 The head 17a of the bolt 17 is flattened on the lower side, in a horizontal plane with the lower-most element of the shank of the bolt. In performing the shimming operation, sufficient shims may be inserted so that, when the bolster is lowered, the bolt 17 may just be inserted in its opening. If the bolt 17 cannot be inserted, the shimming operation has been carried to excess, and a sufficient number of shims must be removed to allow the bolt 17 to go into place.
- 15 When a car truck is initially placed in service no shims are present or necessary. However, as the use of the truck continues, the springs gradually lose a certain amount of their strength and resiliency, with a consequent lowering of the 20 car frame. Also, after a certain length of time in service, the truck wheels will have to be turned down, thus affecting the height of the car frame. These effects must be compensated by shimming. To accomplish this operation in accordance with 25 my invention, the bolster is first raised as high as possible in the bolster openings by means of jacks, the bolt 17 being at this time removed from the side frame. When the bolster has been so raised, the dowels 4a will be entirely clear of 30 the bosses 10 and the openings 4, and the desired number of shims 12 may be dropped over the bosses onto the tops of the springs caps 8. The shims 13 are inserted by raising the springs 11 and discs 11a, the compression having been 35 removed from said springs, and simply inserting the shims between the discs 11a and the spring seat 3. The bolster is then lowered to complete the operation. When the springs 11 and discs 11a are fastened to the bolster, as shown in 40 my pending application above referred to, said springs and discs are automatically raised as the bolster is jacked up, whereupon the insertion of the shims 13 is facilitated.
- 45 As illustrated in Figs. 3 and 4, a further feature of my invention is the provision of means for shimming the inner sides of the column 19 forming the bolster opening 1a to compensate for wear resulting from friction between the bolster 2 and the column 19. In carrying out this phase of 50 the invention, shims 20 are interposed between the columns 19 and the sides 2a of the bolster 2. The shims 20 are of a vertical dimension corresponding to the height of the bolster opening, and are of a cross-section corresponding in shape to 55 that of the respective columns 19. The shims 20 may be of any suitable thickness of material, sufficient to compensate for such a degree of wear as serves to make shimming desirable.
- To insert the shims 20 into position, it is necessary to effect a relative lateral movement between 60 the side frame 1 and the bolster 2, so as to withdraw the latter from the bolster opening 1a. This is done by raising the bolster by means of jacks, after which the side frame is removed 65 from the car truck. The shims 20 are then put in place adjacent the columns 19 and the side frame replaced in position, the bolster being then lowered into place. It is obvious that no special means need be provided for maintaining the 70 shims 20 in place, since they are effectively retained in position by engagement with the bolster 2. The shimming operation just described may of course be performed at the same time and as a part of the spring shimming operation. However, in most cases the occasions for the two oper-

ations will not coincide in time, and for that reason the operations are separately described.

Figs. 5 and 6 illustrate a modification of my invention, in which means are provided for carrying on the bolster a supply of shims of both of the necessary types for shimming the springs. The bolster 2 of Fig. 5 differs from that of Fig. 1 in that it possesses the openings 14 through which the rods 15 project downwardly into the dowels 4a. The latter are partially closed at the bottom, 10 the openings 4b, however permitting the passage of the bosses 10. The rods 15 are reduced, at the lower end, as at 16, to the diameter of the bosses 10.

A supply of shims 12 and 13 are carried on 15 top of the bolster 2, the shims 12 being so placed that their central openings embrace the upper ends of rods 15. Shims 13 are disposed in interlocking relation to shims 12, as is shown in Fig. 6. So long as rods 15 continue to project above 20 the top of bolster 2, therefore, the shims 12 and 13 are prevented from moving out of place. When it is desired to perform the shimming operation, the bolster is raised by jacks as already 25 described. When this is done, the rods 15, being free to move in the bolster, will move downwardly with respect thereto until the reduced portions 16 have entered the openings 4b as far as possible. By this movement the upper ends of rods 15 will be withdrawn from the shims 12, and the latter, as well as shims 13, may be slid off of 30 the bolster top. The shimming operation is then performed as already set forth.

By the use of this feature of my invention it will be possible to perform the shimming operation, if necessary, while the car is at a point distant from the yards or shops where such operations are usually performed.

In the modified form of my invention illustrated in Figs. 7 and 8, provision is made for 40 compensating for wear between the dowels 4a of the bolster 2 and the sides of the openings 4 in the spring seat 3, through which they project. Referring to Fig. 7, it will be seen that the openings 4 are not circular, but that, throughout a 45 portion of their periphery, they are provided with stepped recesses 30. Arcuate wear members 31, of L-shaped cross-section, are adapted to fit into the recesses 30 and to take the wear resulting from frictional contact with the dowels 50 4a. The inner bolster spring 11 shown in dotted outline in Fig. 7 overlies the members 31 and holds them in position.

The chief wear will occur at the sides of each 55 dowel opening 4 which is nearest the point of contact between car and bolster, the point from which stresses are transmitted through the bolster. The modified construction, therefore, is employed only throughout those portions of the walls of the openings 4.

When sufficient wear has occurred between any 60 dowel 4a and its cooperating wear member 31 to necessitate compensation, a new member 31 may be fitted into the recess 30, the new wear member 31 being a trifle wider than the preceding one when new, in order to compensate for the wear which the dowel 4a has undergone.

The terms employed in the foregoing specifications are terms of description and not of limitation, and I do not wish to be limited to the 70 particular construction disclosed, since various modifications of the same may be made within the scope of the present invention.

What I claim is:

1. In a truck for railway cars, the combination 75

- of a side frame having a bolster opening, a bolster extending into said bolster opening and supported therein by springs, shim members interposed between certain of said springs and said bolster, and shim members interposed between others of said springs and said side frame, for the purpose of maintaining the proper bolster height said shim members being so constructed and arranged that they are positively retained in correct position by portions of said bolster and side frame.
2. In a truck for railway cars, the combination of a side frame having a bolster opening, said side frame being substantially of box-section beneath said bolster opening, a bolster extending into said bolster openings, dowels projecting downwardly from said bolster, springs positioned within said box-section portion of said side frame, and adapted to support said bolster, a spring cap upon each said spring, said spring caps being adapted ordinarily to engage said downwardly projecting dowels on said bolster, and one or more shim members interposed between each said spring cap and its co-operating dowel for the purpose of compensating for causes tending to diminish the bolster height and means associated with said spring caps for retaining said shims in position.
3. In a car truck the combination of a side frame and bolster each having upper and lower spring seating portions, a plurality of springs positioned between said seating portions on said side frame and bolster, certain of said springs being positioned entirely above others of said springs, shims between the lower springs and the lower spring seating portion of the bolster, other shims between the upper springs and the upper spring seating portion of the side frame and retained in place by engagement with said bolster, and means associated with said lower spring seating portion of the bolster to hold the shims in position.
4. In a truck for railway cars, the combination of a side frame provided with a bolster opening having a spring seat at the bottom thereof, the said frame being substantially of box-section beneath the bolster opening, spring bearing elements positioned on said spring seat, a bolster extending into said bolster opening, dowels projecting downwardly from said bolster, springs positioned within said bolster and adapted ordinarily to seat on said bearing elements, springs positioned within said box-section portion of said side frame, spring caps resting upon said latter springs and adapted ordinarily to engage said downwardly projecting dowels on said bolster, one or more shim members interposed between said bearing elements and said spring seat and held in place by partially surrounding said dowels, one or more shim members interposed between said spring caps and said dowels on said bolster and means associated with said spring caps for retaining said latter shims in position.
5. In a truck for railway cars, the combination of a side frame having a bolster opening, a bolster extending into said bolster opening and supported therein by springs, a plurality of shim members, and means associated with said bolster for carrying said shim members, said carrying means being adapted to prevent the removal of said shim members except when said bolster has been raised relative to said carrying means as in performing the shimming operation.
6. In a truck for railway cars, the combination of a side frame having a bolster opening, a bolster extending into said bolster opening and supported therein by springs, said bolster having openings in the top thereof, and rods positioned within said bolster and projecting through said openings in the top thereof, said rods being likewise supported by said springs, and being capable of independent vertical movement with respect to said bolster, whereby when said bolster is raised by external means said rods will continue to rest upon said springs.
7. In trucks for railway cars, the combination of a side frame having a bolster opening, a bolster extending into said bolster opening and supported therein by springs, said bolster having openings in the top thereof, and rods positioned within said bolster and projecting through said openings formed in the top thereof, said rods being likewise supported by said springs, and being capable of independent vertical movement with respect to said bolster, whereby when said bolster is raised by external means said rods will continue to rest upon said springs until the bolster has been raised a predetermined distance.
8. In a truck for railway cars, the combination of a side frame having a bolster opening, a bolster extending into said bolster opening, said bolster being supported in position by springs, means for shimming said springs to compensate for causes tending to diminish the bolster height, and removable means extending into the bolster opening above said bolster for providing an indication when said shimming operation has been carried to the practicable limit.
9. In a truck for railway cars, the combination of a side frame having a bolster opening, a bolster extending into said bolster opening and supported therein by springs, means tying said bolster and side frame together, means associated with said bolster and said side frame for compensating for causes tending to diminish the bolster height, and shimming means associated with said bolster and said side frame for compensating for wear occurring therebetween, the last mentioned means being held in position by said side frame and said bolster.
10. In a truck for railway cars, the combination of a side frame having a bolster opening, a bolster extending into said bolster opening, means for holding said bolster and side frame in assembled position and means associated with and held in position by said bolster and said side frame for compensating for wear occurring therebetween.
11. In a truck for railway cars, the combination of a side frame having a bolster opening, a bolster extending into said bolster opening, said side frame and bolster interfitting with each other to retain the same in assembled position and shim members interposed between said bolster and the walls of said bolster opening for compensating for wear occurring therebetween, said shim members being held in position by said walls and said bolster.
12. In a truck for railway cars, the combination of a side frame having a bolster opening formed by spaced columns, a bolster extending into said bolster opening, said columns having portions extending into overlapping relation to an end of said bolster, and shim members interposed between said bolster and the walls of said bolster opening, including said extending portions, for compensating for wear therebetween, said shim members being held in position by said walls and said bolsters and being confined ver-

- tically by horizontal portions of the side frame defining the bolster openings.
13. In a truck for railway cars, the combination of a side frame having a bolster opening, 5 a spring seat beneath said bolster opening, said spring seat having openings therein, a bolster extending into said bolster opening and supported by springs, said bolster having dowels projecting through said openings in said spring seat, 10 means for compensating for causes tending to diminish the bolster height, and means for compensating for wear between said bolster and said side frame, said wear-compensating means including means for compensating for wear between said bolster and the walls of said bolster opening and means for compensating for wear between said dowels and the walls of said openings in said spring seat.
14. In a truck for railway cars, the combination of a side frame having columns defining a 20 bolster opening, each of said columns comprising a portion extending transversely of the side frame, and a portion extending longitudinally thereof into overlapping relation to an end of the bolster, a bolster extending into said bolster opening, and shim members interposed between said bolster and said columns, each of said shim members comprising a portion extending parallel to the transverse portion of the corresponding column and further comprising a portion extending into overlapping relation to said bolster end and parallel to the longitudinally extending 25
- portion of said column and being confined vertically by horizontal portions of the side frame defining the bolster openings.
15. In a truck for railway cars, a side frame having columns defining a bolster opening, each 5 of said columns having a portion extending transversely of the side frame, and a portion extending longitudinally thereof into overlapping relation to an end of the bolster, a bolster extending into said bolster opening, and shimming members interposed between said transversely extending portions of the respective columns and the adjacent side walls of the bolster and overlapping said bolster end, said shim members being held in position by said bolster side walls and said transversely extending column portions and being confined vertically by horizontal portions of the side frame defining the bolster openings.
16. In a truck for railway cars, the combination of a side frame having a bolster opening, a 20 bolster extending into said bolster opening, and means for compensating for wear between said bolster and said side frame, said means being confined vertically by walls of said opening and engaging transversely and longitudinally extending 25 surfaces on said side frame and bolster and being held in position thereby, said means and said longitudinally extending surfaces of the side frame extending into overlapping relation to an end of the bolster.

JAMES A. SHAFER.
